(57) CLAIM

The ornamental design for a ceiling fan wall controller, as shown and described.

DESCRIPTION

FIG. 1 is a perspective view of a ceiling fan wall controller showing my new design in a preferred form.

FIG. 2 is a front view thereof.

FIG. 3 is a right side view thereof.

FIG. 4 is a left side view thereof.

FIG. 5 is a top view thereof.

FIG. 6 is a bottom view thereof.

FIG. 7 is a rear view thereof.

FIG. 8 is a perspective view of a ceiling fan wall controller in another preferred form.

FIG. 9 is a front view thereof.

FIG. 10 is a right side view thereof.

FIG. 11 is a left side view thereof.

FIG. 12 is a top view thereof.

FIG. 13 is a bottom view thereof; and,

FIG. 14 is a rear view thereof.

The broken line showing of the environment is for illustrative purpose only and forms no part of the claimed design.
